UNITED STATES PATENT OFFICE.

CHARLES D. LA PORT, OF CARSON, IOWA.

WASHING-MACHINE.

SPECIFICATION forming part of Letters Patent No. 396,498, dated January 22, 1889.

Application filed March 29, 1888. Serial No. 268,870. (No model.)

To all whom it may concern:

Be it known that I, CHARLES D. LA PORT, a citizen of the United States, residing at Carson, in the county of Pottawattamie and State 5 of Iowa, have invented certain new and useful Improvements in Washing-Machines, of which the following is a specification, reference being had therein to the accompanying drawings.

10 This invention relates to certain new and useful improvements in washing-machines; and it consists in a certain novel combination and arrangement of parts, as will be herein-after more fully set forth in the specification, 15 and be pointed out in the claims.

The object of this invention is to provide a cheap and simple washing-machine and one whose parts shall be so constructed that they cannot readily get out of order.

20 Another object of my invention is to provide a washing-machine of that class whose sides and bottom are provided with protuberances so constructed that the action of the agitator over the clothes, in connection with 25 the protuberances upon the sides and bottom, shall simulate the action of a person's knuckles upon an article between the hands and the wash-board ordinarily used.

In the accompanying drawings, forming a 30 part of this specification, and on which similar letters of reference indicate the same or corresponding features, Figure 1 is a longitudinal vertical sectional view through my improved washing-machine, and Fig. 2 is a 35 transverse sectional view through the same.

The body of my washing-machine consists of the sides A and B, the end pieces, D E and F G, and the bottom H, the said body being supported upon the diverging legs I I, the 40 same being united at their upper ends and constructed to form bearings for the rock-shaft J, one end of which is provided with a crank, K, and handle L. At a point just beyond the bearings the rock-shaft descends 45 somewhat and is provided with diverging bars M, placed near one another, and on said bars I place a number of balls, N, the bar or rod M extending only a part of the way through the lowest ball, O, said ball being rigidly and 50 securely fastened thereon, so as to present a smooth surface to the clothes which shall be engaged by said bars. The rod extends en-

tirely through the other balls, and they are free to move upon it, being held in place by a spiral spring, P, which surrounds the upper 55 portion of the rod and presses from the rock-shaft against the said balls.

The object of constructing my agitator in this manner is, first, that the diverging rods may catch the clothes between them and thus 60 thoroughly rub them against the semispherical balls upon the sides, ends, and floor of the machine, and, secondly, to allow these balls on the agitator to play along the rod by reason of the spring, and to turn also upon it, so that 65 the action of the agitator upon the clothes will, as nearly as possible, simulate that of the knuckles on a person's hand. It will be observed that I may construct these balls of rubber, wood, celluloid, or any other suitable substance, though I find by actual trial that either 70 wood or rubber gives satisfactory results. Those boards nearest the ends, but composing the top, or rather a portion of the top, of the machine, it will be noticed, are inclined downwardly from their outer ends toward the center of the machine, the purpose of which is to allow of the dripping off of the suds and water splashed against them, and to one of these 75 inclined boards I secure, by hinges or otherwise, as may be desired, a door, Q, and near its farther end I provide the sides of the machine on its upper edge with thumb-clamps R, so that when the door is closed and the thumb-clamps turned said door will be firmly 80 held in place.

I do not wish to be understood as confining myself to the precise construction herein shown and described, for I may somewhat vary it without departing from the spirit of 90 my invention, the essential features of which are, first, the providing an agitator with a series of balls capable of movement both around the rod upon which they are mounted and also in a vertical plane up and down said rod, 95 and, secondly, the providing those portions of the interior of the machine with which the agitator comes in contact with similar balls or semispherical knobs, S, against which the clothes are rubbed when the machine is in 100 action.

Instead of the crank used to rock the rock-shaft, I may employ a lever or any of the usual means for obtaining motion.

Having thus fully described my invention, what I claim as new, and desire to secure by Letters Patent, is—

1. In a washing-machine, the combination, with the body, of an agitator having arms extending out therefrom, balls rigidly secured on the ends of said arms, and a series of balls on the arms above the rigid balls adapted to revolve and move vertically thereon, substantially as described.
2. In a washing-machine, the combination, with the suds-box having hemispherical projections on its inner faces, of an agitator hav-

ing diverging arms extending downwardly therefrom, balls rigidly secured on the outer ends of the arms, a series of rotatable and vertically-movable balls above the said other balls, and springs on the arms for forcing the movable balls down, substantially as described.

In testimony whereof I affix my signature in presence of two witnesses.

CHARLES D. LA PORT.
